UNITED STATES PATENT OFFICE.

CHARLES D. FULLER, OF KALAMAZOO, MICHIGAN.

DESIGN FOR A RUBBING-PLATE FOR WASHBOARDS.

SPECIFICATION forming part of Design No. 23,507, dated July 24, 1894.

Application filed March 9, 1894. SeriNo. 503,061. Term of patent 14 years.

To all whom it may concern:

Be it known that I, CHARLES D. FULLER, a citizen of the United States, residing at Kalamazoo, in the county of Kalamazoo and State of Michigan, have invented or discovered a certain new and original Design for Rubbing-Plates for Washboards, of which the following is a specification.

The invention described herein relates to a certain new and original design for the rubbing plates for washboards.

In the accompanying drawings forming a part of this specification, Figure 1 is a view in elevation of a rubbing plate for washboards embodying my design shown in position in a supporting frame, and Fig. 2 is a transverse section of the same, the plane of section being indicated by the line x, x , Fig. 1.

The leading feature of my design consists of a series of ribs or corrugations transverse of the plate, the upper part or apex of each rib

varying in width at sections or portions along its length, alternate sections or portions being perforated.

The rubbing plate 1 is provided with a series of transverse ribs or corrugations 2. Portions or sections 3 of each of these ribs are widened at their upper ends or apices and the widened apices are perforated as at 4. The sections 3 of one rib alternate with the corresponding sections of the ribs next adjacent.

I claim herein as my invention—

The design for rubbing plates for washboards substantially as herein shown and described.

In testimony whereof I have hereunto set my hand.

CHARLES D. FULLER.
